UNITED STATES PATENT OFFICE.

CHRISTIAN D. WISELOGEL, OF ALBION, MICHIGAN, ASSIGNOR TO UNION STEEL SCREEN COMPANY, LIMITED, OF ALBION, MICHIGAN.

RACK.

993,491.

Specification of Letters Patent. Patented May 30, 1911.

Application filed May 27, 1910. Serial No. 563,837.

To all whom it may concern:

Be it known that I, CHRISTIAN D. WISELOGEL, a citizen of the United States, residing at Albion, Michigan, have invented certain new and useful Improvements in Racks, of which the following is a specification.

This invention relates to improvements in racks.

My improved rack is especially designed 10 by me for the use of bakers, although it is adapted for use in various other relations.

The main objects of this invention are: First, to provide an improved rack which is simple in construction and easily cleaned 15 and one in which all the shelves are readily accessible and removable. Second, to provide an improved rack which is very rigid and capable of carrying heavy loads, although made of comparatively light material. Third, to provide an improved rack 20 in which the uprights and horizontal frame members are connected in a manner that avoids the necessity of bracing.

Further objects, and objects relating to 25 structural details, will definitely appear from the detailed description to follow.

I accomplish the objects of my invention by the devices and means described in the following specification. The structure described constitutes one effective embodiment 30 of my invention. Other embodiments would be readily devised by those skilled in the art.

The invention is clearly defined and 35 pointed out in the claims.

A structure constituting an effective and preferred embodiment of the features of my invention is clearly illustrated in the accompanying drawing, forming a part of this 40 specification, in which:

Figure 1 is a detail side elevation of a structure embodying the features of my invention. Fig 2 is a vertical transverse section taken on a line corresponding to line 45 2-2 of Fig. 1, a single rack only being shown in position. Fig. 3 is a detail perspective showing one of the bottom corner members with the vertical and horizontal frame pieces secured thereto. Fig. 4 is a detail plan view of one of the top members, showing the upright and horizontal members secured thereto. Fig. 5 is a detail horizontal section taken on a line corresponding 50 to line 5-5 of Fig. 1. Fig. 6 is a horizontal section taken on a line corresponding to line 55

6-6 of Fig. 1. Fig. 7 is a detail perspective of one of the shelves.

In the drawings, similar reference characters refer to similar parts throughout the several views, and the sectional views are 60 taken looking in the direction of the little arrows at the ends of the section lines.

Referring to the drawing, my improved rack consists of the upright corner pieces 1, the horizontally disposed top and bottom 65 side pieces 2 and 3, respectively, and the horizontally disposed top and bottom end pieces 4 and 5, respectively. The frame pieces are formed of angle iron, as illustrated. These frame pieces are connected by 70 top and bottom corner members.

The bottom corner members consist of base or horizontal plates 6, having vertically disposed flanges 7 and 8 thereon, the flanges being disposed at right angles to each other. 75 The horizontal bottom side and end pieces 3 and 5 are arranged in the angles formed by these flanges, the side pieces being arranged with the angles facing upwardly, while the end pieces are arranged with their 80 angles facing downwardly so that their horizontal legs are in substantially the plane of the upper edges of the side pieces and are adapted to serve as shelf ledges, as clearly appears from Figs. 2 and 3.

The side flange 7 of the bottom corner member projects beyond the flange 8 to form an outwardly-facing angle 9 for the corner uprights, see Figs. 3 and 6. The flanges are preferably extended upwardly 90 at the corner to afford suitable means for attaching the corner uprights to the corner members. The top corner members are provided with horizontal portions or base plates 10 having flanges 11 and 12 thereon to 95

which the top side and end pieces 2 and 4, respectively, are secured. The flange 11 is extended beyond the flange 12 to provide an angle 13 for the upper ends of the uprights, see Figs. 4 and 5. By thus forming the corner members and securing the frame pieces thereto, the rack is made rigid without the aid of braces, which is of advantage not only in the economy of construction, but also in convenience in use and in keeping 105 the rack in a sanitary condition.

The caster wheels 14 are secured to the corner member base plate 6, it being provided with suitable holes 15 for the caster securing bolts, see Fig. 3. The shelves 16 110

are supported on ledges 17. These ledges are formed of angle iron, and are preferably arranged with their angles facing inwardly, the vertical legs thus serving as a means for 5 preventing longitudinal movement of the shelves in the rack, and the horizontal legs serving as supports. The ends of the horizontal legs of the ledge pieces are preferably turned up to form stops 18 for the shelves.

10 These shelves are formed of metal and consist of suitable longitudinal pieces or bars having cross bars secured thereto, see Fig. 7

By arranging the parts as I have illustrated and described, I provide a rack which 15 is easily kept in a sanitary condition, and is very convenient to use, and while the same is economical to produce, it is very strong and rigid.

Having thus described my invention, 20 what I claim as new and desire to secure by Letters Patent is:

1. In a rack, the combination of the angle iron upright corner and horizontally-disposed top and bottom side and end pieces; 25 and top and bottom corner members, each comprising a base plate or portion having flanges disposed vertically at right angles to each other, the flange at the side of the plate being extended beyond the 30 flange at the end of the plate to provide an outwardly-facing angle, said corner pieces

being arranged in the outwardly-facing angles of said corner members, the said side and end pieces being arranged in the horizontal angles thereof, the bottom end pieces 35 being arranged with their angles facing downwardly so that their horizontal legs are in the plane of the upper edges of the bottom side pieces and adapted to serve as shelf ledges.

2. In a rack, the combination of the angle-iron upright corner and horizontally-disposed side and end pieces and corner members comprising base plates or portions having flanges disposed vertically at right angles to each other to which said top and bottom side and end pieces are secured, said side and end pieces being arranged in the horizontal angles of said corner members, and said uprights being arranged in the outwardly-facing angles of said corner members; and angle-iron rack ledges secured to the inwardly-projecting legs of said uprights with their angles facing upwardly.

In witness whereof, I have hereunto set 55 my hand and seal in the presence of two witnesses.

CHRISTIAN D. WISELOGEL. [I. S.]
